(57) **CLAIM**

The ornamental design for an adhesive ankle support brace, as shown and described.

DESCRIPTION

FIG. 1 is a top view of an adhesive ankle support brace showing our new design;

FIG. 2 is a first perspective view thereof;

FIG. 3 is a second perspective view thereof; and,

FIG. 4 is a third perspective view thereof.

It is understood that the adhesive ankle support brace shows no appreciable thickness.

The broken lines shown in the drawings illustrate environmental structure and form no part of the claimed design.
